ATTORNEYS.

UNITED STATES PATENT OFFICE.

JOHNSON D. LANGSTON, OF BIRMINGHAM, ALABAMA.

OIL BURNER.

Application filed March 29, 1922. Serial No. 547,600.

To all whom it may concern:

Be it known that I, JOHNSON D. LANGSTON, a citizen of the United States, and a resident of Birmingham, in the county of Jefferson and State of Alabama, have invented certain new and useful Improvements in Oil Burners, of which the following is a specification.

The principal object of this invention is to provide an oil burner adapted to be inserted into any existing cooking stove, range or heater without requiring any great amount of alteration or change to the existing structure.

15 A further object is to provide a new and improved burner in which means are provided for protecting the superheating coil from cooling currents of cold air.

Another object is to so construct the superheating bowl that it will encase and protect the superheating coil from cold air currents, and

25 A further object is to provide a new and improved burner that will generate a high degree of heat with a small consumption of fuel.

For the accomplishment of these and such further objects as will hereinafter be apparent to those skilled in the art to which 30 this appertains, the invention consists in the construction, combination and arrangement of parts herein specifically described and illustrated in the accompanying drawings, wherein is shown a preferred embodiment of the invention, but it is to be understood that changes, variations and modifications may be resorted to which fall within the scope of the claims hereunto appended.

40 In the drawings forming a portion of this specification:

Fig. 1 is a plan view of my improved burner.

Fig. 2 is a section on the line 2—2 of Fig. 1 and

45 Fig. 3 is a section on the line 3—3 of Fig. 1.

As shown in the drawings, an air circulating drum 10 is provided with a plurality of lugs 11 which are adapted to engage with 50 and support an annular outwardly projecting flange 12 formed upon the upper part of a superheating bowl 13 which as shown is preferably of a semi-spherical contour. A fuel feed pipe 14, having a cut off valve 55 14^a is formed into an inverted U shaped portion 15 upon the horizontal reach 16 of

which is secured a deflector plate 17, the upper portion of the circulating drum preferably being slotted as at 18 to engage the lower ends of the vertical portions of the U. 60 The feed pipe terminates adjacent the U portion in an inwardly directed bend 19 to which is secured one end of a helically wound superheating and generating coil 20, the other end of which coil is curved downwardly around the inner lower surface of the bowl 13 and then upwardly through the centre of the coil terminating in a fuel nozzle 21, the axis of which is in alignment with the center of the deflector plate 17. 70 The plate 17 is preferably provided with a series of lugs 17^a to prevent warping or buckling.

The operation of the burner is as follows:

A small quantity of fuel is allowed to flow 75 into the superheating bowl 13 in the usual manner and upon being ignited it will heat the superheating coil 20 to a sufficient temperature to volatilize the fuel which will be projected against the deflector plate 17 where 80 it will be ignited. The air supply will flow upwardly through the annular space between the air drum and superheating bowl and due to the presence of the superheating bowl, there will not be a sufficient supply of oxygen 85 to permit the combustion of the fuel until it strikes the deflector plate, the intervening space between the fuel nozzle 21 and the deflector forming a neutral zone.

As the superheating bowl completely encases the superheating coil on its lower side, the cool air supply is prevented from contacting with the superheating coil and cooling it. It will thus be seen that a higher working temperature of the coil will be 90 maintained and because of the arrangement whereby the fuel is prevented from igniting until it strikes the deflector plate, a greater efficiency of operation is obtained due to the expansion of the fuel jet as it passes 100 through the neutral zone and the consequent breaking up of the fuel particles. Again due to the presence of the feed pipe 14—16 over the flame, the fuel will receive a pre-heating before it reaches the super-heating. 105

Having thus described my invention what I claim as new and desire to secure by Letters Patent, is:

1. In a burner, an air drum, a superheating coil, terminating in a fuel nozzle, a deflector plate spaced from said nozzle, a generating bowl partially encasing said coil, 110

said bowl and coil spaced from and below said deflector within said air drum to deflect the air supply currents and define a neutral zone whereby the combustion of fuel ⁵ will be prevented until said fuel reaches said deflector plate.

2. In a burner, an air drum, a superheating coil mounted within said air drum, a feed pipe connected with said superheating coil, a deflector plate supported by said feed pipe, a generator bowl constructed and arranged to partially encase said coil and prevent contact of the cool air current with said coil and a portion of said feed pipe passing ¹⁰ through the flame region whereby a pre-heating of the fuel is obtained before it reaches the superheating coil.

3. An oil burner comprising an air drum, said drum provided with means to support a

feed pipe, a super-heating coil attached to ²⁰ said feed pipe, a fuel nozzle, a preheating bowl constructed and arranged to partially encase said coil and means carried by said drum to support said bowl.

4. An oil burner comprising an air drum, ²⁵ said drum provided with means to support a feed pipe, a super-heating coil having one of its ends attached to said feed pipe, a fuel nozzle secured on the other end of said coil and a preheating bowl spaced from said drum to allow a passage for the air supply ³⁰ between said bowl and drum said bowl encasing the lower side of said coil to prevent cooling of said coil by said air supply.

Signed at Birmingham, in the county of ³⁵ Jefferson and State of Alabama, this 13th day of March A. D. 1922.

JOHNSON D. LANGSTON.
